Primary Examiner — Holly Baynham(74) *Attorney, Agent, or Firm* — Dinsmore & Shohl LLP; Mark D. Schneider(57) **CLAIM**

The ornamental design for a sleeve case, as shown and described.

DESCRIPTION

FIG. 1 is a front perspective view of the sleeve case with the broken lines showing the strap and clasps being for the purpose of illustrating environment and forming no part of the claimed design.

FIG. 2 is a planar view of a front face of the sleeve case of FIG. 1;

FIG. 3 is a planar view of a rear face of the sleeve case of FIG. 1;

FIG. 4 is a planar view of one side of the sleeve case of FIG. 1;

FIG. 5 is a planar view of an opposite side of the sleeve case of FIG. 1;

FIG. 6 is a planar view of a top of the sleeve case of FIG. 1; and,

FIG. 7 is a planar view of a bottom of the sleeve case of FIG. 1.
